UNITED STATES PATENT OFFICE.

HENRY FRESH, OF CUMBERLAND, MARYLAND, ASSIGNOR TO EMERGENCY CAR BRAKE COMPANY, OF CUMBERLAND, MARYLAND.

BRAKE-SHOE.

SPECIFICATION forming part of Letters Patent No. 766,437, dated August 2, 1904.

Application filed February 2, 1904. Serial No. 191,704. (No model.)

To all whom it may concern:

Be it known that I, HENRY FRESH, a resident of Cumberland, in the county of Allegany and State of Maryland, have invented certain new and useful Improvements in Brake-Shoes; and I do hereby declare the following to be a full, clear, and exact description of the invention, such as will enable others skilled in the art to which it pertains to make and use the same.

10 The invention relates to brake-shoes for railway-rails such as patented to me January 13, 1903, such patent being numbered 718,488; and its objects are to provide such shoes with a conveniently-detachable sole or friction-plate holder, a durable and efficient friction-plate, and combinations of such parts.

The invention consists in the construction hereinafter described and pointed out.

In the accompanying drawings, which form part of this specification, Figure 1 is a side elevation of the improved brake-shoe. Fig. 2 is a vertical section passing through the shoe and through the trunnion connecting its body and friction-plate holder. Fig. 3 is a side elevation of a friction-plate holder. Fig. 4 is a bottom plan of the shoe-body. Fig. 5 is a partial section of the body. Fig. 6 is a section on line $x-x$ of Fig. 1.

Numeral 1 denotes the main body of the shoe, and 2 the friction-plate holder. The former has a seat or bearing 3 for a trunnion or rounded rib 4, connected by a web with a friction-plate holder or shoe-sole.

Means for supporting the shoe are indicated at 1^x in Fig. 1, which support, if desired, may be of substantially the character described in my patent aforesaid.

The seat or bearing 3 and trunnion 4 are by preference approximately half as long as the main part 1 of the shoe, and said trunnion fills the seat, but fits it sufficiently loosely to permit its turning in the seat or bearing, whereby the holder is automatically rocked by pressure against the track-rail to automatically effect a direct bearing thereon of the friction-plate 6, fitted in said holder.

The upper faces or shoulders 7 of the holder are downwardly inclined from the web to the outer sides to permit the rocking of the holder

under the bottom on the main part 1 of the shoe.

8 denotes a concealed screw or the like entered in a transverse seat formed partly in the body 1 and partly in the trunnion 4 to insure a stable connection of the parts. This screw 55 is shorter than the thickness of the shoe-body and is inserted in a suitable hole, opening at the inside only, whereby its concealment is effected.

9 denotes a groove in the bottom of the body 1 to receive a rib 10 on the holder. The groove extends from the trunnion-seat to the toe or end of the body and the rib a little farther, the purpose of this construction being to aid in preventing relative lateral displacement of either the body or holder.

11 denotes the front end of the holder, beveled substantially as indicated, whereby it is adapted to remove snow, ice, or other obstructions from a track-rail.

A friction-plate 6, preferably made of compacted felt of wool, is forced by hydraulic pressure into an undercut seat 13, extending from the rear of the holder to near its forward end.

I have found woolen felt to be specially suited by its durability, non-conductivity, elasticity, and frictional capacity for use in a friction-plate. Preferably such plate will protect below its holder. When sufficiently worn to fail as a friction device or as a defense to the holder, it can be readily removed and replaced by a fresh plate.

Having described my invention, what I claim as new, and desire to secure by Letters Patent, is—

1. The combination of a shoe-body and a laterally-rocking friction-plate holder.
2. The combination of a shoe-body and a laterally-rocking friction-plate holder, said plate and holder being connected by the trunnion.
3. The combination of a shoe-body and a laterally-rocking friction-plate holder, said holder having upper surfaces inclined upwardly at an angle toward the center of the bottom face of the body.
4. The combination of the body and the

friction-plate holder, one of the said parts being provided with a loosely-fitting rib to prevent the relative lateral displacement of either.

5. The combination of the body, the friction-plate, and the friction-plate holder, said holder having its forward edge beveled downwardly toward its front to clear a track-rail.

6. The combination of the body, the holder and a single concealed transverse screw to secure them in operative relation.

7. The combination of the body, the holder, and the friction-plate of woolen felt.

8. The combination of the body, the holder, and the friction-plate of woolen felt, said felt

plate being compacted and pressed into a seat 15 in the holder.

9. The combination of the body, the holder, and the friction-plate of woolen felt, said felt being compacted and pressed into an undercut seat in the holder. 20

In testimony whereof I have signed this specification in the presence of two subscribing witnesses.

HENRY FRESH.
